Primary Examiner — Selina Sikder(74) *Attorney, Agent, or Firm* — Kunzler Bean & Adamson(57) **CLAIM**

The ornamental design for a control panel, as shown and described.

DESCRIPTION

FIG. 1 is a top, exploded perspective view of a control panel and a wall mount (with the wall mount shown in phantom lines); and,

FIG. 2 is a rear, bottom perspective view of the control panel of FIG. 1 attached to a wall mount (with the wall mount shown in phantom lines).

The broken lines in the drawings depict portions of the control panel that form no part of the claimed design.

1 Claim, 2 Drawing Sheets(56)
